UNITED STATES PATENT OFFICE.

WILLARD A. SPEAKMAN, OF WILMINGTON, DELAWARE.

DESIGN FOR A BATH WATER-DISTRIBUTING FIXTURE.

45,574.

Specification for Design.

Patented Apr. 7, 1914.

Application filed December 12, 1912. Serial No. 736,420. Term of patent 14 years.

To all whom it may concern:

Be it known that I, WILLARD A. SPEAKMAN, a citizen of the United States, residing at Wilmington, in the county of Newcastle, in the State of Delaware, have invented a new, original, and ornamental Design for a Bath Water-Distributing Fixture, of which the following is a specification, reference being had to the accompanying drawing, forming part thereof.

The figure is a perspective view of a bath water distributing fixture of the kind commonly called a "shower body."

This fixture comprises an elongated body, having a globular central portion and globu-

lar end portions and terminating in convex unapertured end surfaces.

The front aperture of the fixture as shown in the figure are intended to each receive a corresponding valve spindle and pipes are intended to be connected in the other aperture and to the downturned end portions of the fixture.

I claim:

The ornamental design for a bath water distributing fixture, as shown and described.

WILLARD A. SPEAKMAN.
